(57) **CLAIM**

The ornamental design for a game board as shown and described.

DESCRIPTION

FIG. 1 is a front perspective view of a game board showing my new design;

FIG. 2 is a front perspective view in an environment of use;

FIG. 3 is a front elevation view thereof;

FIG. 4 is a rear elevation view thereof;

FIG. 5 is a top plan view thereof;

FIG. 6 is a bottom plan view thereof;

FIG. 7 is a left side elevation view thereof; and,

FIG. 8 is a right side elevation view thereof.

The broken lines in the drawings illustrate portions of the game board that form no part of the claimed design. The broken lines in FIG. 2 showing the game pieces are for the purpose of illustrating environmental subject matter and form no part of the claimed design. The stippling in the drawings illustrates shading and not a surface pattern.

1 Claim, 5 Drawing Sheets
